CLASP COMPRISING INTERLOCKING MEMBERS HAVING MATCHING SURFACES

Gladys Snyder, Toronto, Ontario, Canada

Application June 18, 1947, Serial No. 755,377

1 Claim. (Cl. 24—201)

1

The present invention relates to a fastener for detachably connecting the ends of articles such as necklaces, bracelets, and beads.

The object of the invention is to provide a fastener for articles of the type mentioned which may be economically manufactured due to its simple construction, and which is of an attractive appearance suited for use in conjunction with ornaments.

It is a further object of the invention to provide a fastener which is readily and simply connected and disconnected, and which, when connected, provides a sure fastening for the article even under extreme conditions of activity on the part of the wearer.

With these and other objects in view, the invention generally comprises a top and a bottom lamina, the bottom lamina having a staple fixed along a portion of its longitudinal axis, one end of the article to be detachably connected being attached to said staple, the other end of said article being attached to the top lamina. The top lamina is provided with an orifice having a width sufficiently great to permit the passage of said bottom lamina therethrough when the longitudinal axes of the two laminae are substantially at right angles but not under any other conditions, said orifice being shaped so as to snugly receive said staple, and to hold the two laminae in face-to-face fixed abutment when tension is applied to the two ends of the article to be detachably connected, after passage of said bottom lamina through the orifice in said top lamina and reception of said staple in said orifice.

Other objects of the invention will be made apparent from a study of the following specification in conjunction with the accompanying drawings.

In the drawings—

Figure 1 is a plan view looking down upon the fastener of my invention in a connected position.

Figure 2 is a side view of the fastener, again in a connected position.

Figure 3 is a cross-sectional view of the fastener taken along the line 3—3 of Figure 2.

Figure 4 is a perspective view of a modification of the fastener according to my invention, showing the bottom lamina inserted through the top lamina but not in the connected position, and

Figure 5 is a perspective view of the modification of Figure 4 showing the bottom lamina being inserted through the top lamina.

In the drawings, like reference characters indicate like parts throughout the figures. In the accompanying drawings 10 is a bottom lamina

having a staple 11 disposed along the longitudinal axis thereof. One end 12 of the article to be detachably connected is attached to the staple 11. A top lamina 13 has the other end 14 of the article to be detachably connected attached to a staple 15 fixed to the upper surface of top lamina 13 and disposed along a portion of the longitudinal axis thereof. The top lamina 13 has an orifice 16 having a width sufficiently great to permit the passage of the bottom lamina 10 therethrough, when the longitudinal axes of the two laminae are substantially at right angles but not under any other conditions. Orifice 16 is also cut away so as to snugly receive the staple 11 when the two laminae are aligned in face-to-face abutment with their two longitudinal axes in the same plane.

It will be seen that if bottom lamina 10 is inserted through orifice 16 in top lamina 13, and the two laminae aligned in face-to-face abutment with staple 11 snugly received by the cut away portions of said orifice 16, then if tension is applied to two ends 12 and 14 of the article to be detachably connected, a secure fastening will be formed.

I prefer to make top lamina 13 wider than bottom lamina 10 and to provide top lamina 13 with two side bars 17 and 18, one side bar being disposed along each longitudinal edge of the under surface of top lamina 13. Side bars 17 and 18 are adapted to prevent angular movement of bottom lamina 10 relative to top lamina 13, when the two laminae are disposed in face-to-face abutment with staple 11 snugly received in the cut away portions of orifice 16.

Figures 4 and 5 show a modification of the fastener according to my invention, in which the end 12 of the article to be detachably connected is made in the form of a relatively large link. With this modification, I do not employ side bars but depend upon the action of this link 12 in conjunction with the snug reception of staple 11 in the cut away portions of orifice 16, to restrain bottom lamina 10 from angular movement with respect to top lamina 13, when the two laminae are in the connecting position previously described. When in this position, tension applied to ends 12 and 14 of the article cause large link 12 to bear flushly against the upper surface of top lamina 13, giving a jamming effect.

From the above specification and from the accompanying drawings, it will be seen that I have disclosed a fastener which meets the objects previously set out as desirable.

It is intended that the present disclosure

should not be limited in any way other than that indicated by the scope of the following claim.

What I claim as my invention is:

A clasp of the class described comprising a first member and an orificed second member, matching principal surfaces on said first and second members, a staple extending from the matching principal surface of said first member to a height substantially less than the width of said first member, the longitudinal axis of said staple 10 being substantially perpendicular to the width of said first member, the length of the orifice in said second member being of sufficient dimensions to accommodate the width of said first member and to snugly receive said staple when said matching surfaces abut in clasping relationship, the maximum width of said orifice being substantially less than the width of said first member and the length of said staple and being of sufficient di- 15

mensions to accommodate the elevation of the staple on the first member together with a chain attachable thereto when said first member is passed through said second member.

GLADYS SNYDER.
